ABSTRACT

A pipe forms a spray nozzle for use in a fluidized bed apparatus, the pipe having spray apertures in its lower portion and having a pointed, steeply sloping cover over its upper portion.

1 Claim, 2 Drawing Figures

Fig.4.

1

SPRAY NOZZLE FOR FLUIDIZED BED APPARATUS

REFERENCE TO RELATED APPLICATION

This is a continuation of application Serial No. 152,888 filed June 14, 1971, now abandoned.

BACKGROUND OF THE INVENTION

A nozzle inserted into or above a fluidized bed will have lumps of melted or otherwise aggregated material form or cake on it. These large lumps will fall from the nozzle to clog the product removal openings and render the apparatus inoperative until cleaned. The nozzle of this invention reduces the possibility of material collecting on it to form large lumps and it better distributes a spray.

BRIEF DESCRIPTION OF THE DRAWING

FIG. 1 is a longitudinal, vertical section through a fluidized bed apparatus showing a nozzle according to this invention disposed therein; and

FIG. 2 is a transverse section through the nozzle of this invention taken on line 2-2 of FIG. 1.

DESCRIPTION OF THE PREFERRED EMBODIMENT

As shown in FIG. 1, a blower 10 forces air through duct 11 to the gas fired heater 12 from which hot gases

5 pass through duct 13 to the base 14 of chamber 15. The hot gases pass upward through the perforated plate 16 to fluidize material in a fluidized bed 17.

10 The nozzle of this invention, designated by the reference numeral 20, enters chamber 15 and has a feed solution introduced therein through fitting 21. As may be seen in FIG. 2, nozzle 20 is a length of pipe or tube 21 having perforations 22 spaced along its lower portion. A sharp peaked cover 23 is welded at 24 and 25 to extend over pipe 21. The cover 23 may be made from sheet metal. Any particles that contact the steep sides 27 of cover 23 will roll off it and thus not build up into large undesirable lumps which could clog the product removal pipe 30 or the screw 31.

15 The perforations 22 can be placed to distribute a solution laterally from nozzle 20 to any extent desired. The perforations 22 can also be placed along nozzle 20 to distribute solution along its length as required.

20 What is claimed is:

25 1. A liquid spray nozzle in combination with a fluidized bed apparatus comprising, in combination, a round pipe containing liquid spray apertures directed downward in its lower portion, and a sheet metal cover welded on the upper portion of said pipe, said cover having steeply sloping sides and a sharply peaked top extending along said pipe within a fluidized bed.
